APPARATUS FOR THE MANUFACTURE OF
SUPERPHOSPHATE AND LIKE PRODUCTS

Dragutin Wellisch, Zagreb, Yugoslavia

Application August 20, 1929, Serial No. 387,238
In Germany February 7, 1929

7 Claims. (Cl. 71—1)

This invention relates to apparatus for the manufacture of superphosphate and the like products.

The chief cause of the defects of the superphosphate reaction chambers hitherto generally employed, resides in the intermittent manner in which they operate.

The present invention aims at providing reaction chambers which are adapted to enable the work to be carried on continuously, in that the reaction mass and the support on which it rests and adheres is moved in relation to that part of the chamber which contains the intake (mixing machine) and the discharge device, so that the dissociated portions of the charge can be conveyed continuously to the discharging device and fresh raw material can be fed into the vacant portion of the chamber.

In the embodiments illustrated in the accompanying drawing, these parts rotate on a horizontal axis.

As the apparatus rotates on a horizontal axis, the stationary hollow cylinder *b* prevents the liquid superphosphate from spreading towards the conveyor. The drum *c* and reaction mass rotate on the horizontal rotational axis *y*—*y*, and accordingly, the mixer *m* and discharging device are stationary whilst the other parts and walls can be connected either to the stationary or the rotary systems, as may be most convenient. The hollow cylinder is provided with an opening of ample dimensions, extending from near the one end wall *a*¹ to the other end wall *a*³ and from the auxiliary wall *a*⁵ to about a line under the knives 14. Through this opening the dislodged material passes into the hollow cylinder, from which it is led into the open by means of any convenient conveyor. The auxiliary wall *a*⁵ is connected with the hollow cylinder and merely serves as a boundary for the dissociation chamber, so that the gases liberated by the dissociation process can be evacuated.

In order to make clear the character of my invention, a preferred embodiment is illustrated in the drawing wherein:

Fig. 1 is a longitudinal section of a cylindrical chamber with a horizontal rotational axis;

Fig. 2 shows the same in cross section, and

Fig. 3 in plan;

Fig. 4 represents a cylindrical chamber with sub-divided cylinder;

Fig. 5 is a cross section of a spherical chamber; and

Fig. 6 shows an annular chamber, the annular space of which is circular in cross section.

In the chambers shown in Figs. 1—3, the stationary portion consists of an end wall *a*¹ in which is placed a hollow cylinder *b*, concentric with the rotational axis. The end wall *a*¹ (in which is sunk the mixer *m*) and the hollow cylinder *b* are held in place by an iron structure. The opposite end wall *a*³ is connected with the cylindrical shell *c*, with which it turns in the direction of the arrow *s*'. The cylinder, which is mounted on rollers *r*, is driven, in the usual manner, by a pinion *r*¹ with driving wheel *r*². The contact surfaces between *a*¹ and *c*, and also between *a*³ and *b*, are self tightening. The auxiliary wall *a*⁵ is disposed vertically and tangentially in relation to the hollow cylinder *b*. It carries the exhaust gas flue *t*, which passes out of the chamber through *a*¹ and is connected with a fan. The discharging device consists of the knife 14, which is disposed at right angles to the rotational axis and is reciprocated in the direction of the double arrow *s*³, by means of the guide rods 15 which slide in the bearing 16 and are moved by a crank or the like. *a*¹ is provided with a slot through which the knife 14 passes out of the interior of the chamber and is thus detached from the block of material. While the knife is in this position the cylinder *c* is moved forward so that, in the next forward movement of the knife the latter encounters a thin layer of material and detaches it from the block. The dislodged material falls through the opening provided in the hollow cylinder on to a conveyor 23 which is disposed in the interior of the hollow cylinder *b* and conveys the dislodged material into the open. The knife 14, and also the auxiliary wall *a*⁵, does not extend down to the cylindrical bottom *c*, and therefore a thin layer of material remains thereon.

If compressed air be used for breaking down the block of material, the requisite pipes are disposed parallel with the rotational axis *y*—*y*, and mounted in the end wall *a*¹. The first of these pipes is situated under the generating line *e*, and the discharged stream of compressed air is directed upwards. The second pipe is above, and staggered in relation to, the first, so that it lies nearer the auxiliary wall *a*⁵, and so on with each succeeding pipe.

Fig. 4 shows a cylindrical chamber in which the cylinder *c* consists of two parts separated by an annular gap, which, in turn, is covered by the cylindrical ring *q*, so that a tight joint is formed. The ring *q* carries the mixer *m* which is thus disposed centrally in relation to the block of material. The end walls *a*¹ and *a*³ are connected to the hollow cylinder *b*, and are carried by an

iron structure. The surfaces of contact with the cylinders *c* are close fitting. The cylinders *c* are mounted on rollers *r*, and are uniformly moved by means of the toothed crowns *z'*. The discharging device consists of a number of knives 14, which are attached to two endless chains 17. These chains, together with the knives, are moved by a toothed wheel not illustrated in the direction of the arrow *s*³, pass out of the chamber through a slot in *a'*, are diverted from this direction of movement by rollers not shown and passed round the outside of the chamber, to be led over other rollers and into the chamber again through a slot in *a³*. This arrangement of the discharging device enables the two cylinders *c* to be moved in a uniform manner. The dislodged material drops through the opening provided in the hollow cylinder *b* and on to the conveyor 23. Instead of being vertically disposed, as shown, the knives may also be arranged parallel with the rotational axis *y*—*y*. The embodiment shown in Figs. 1-3 would be provided with a knife, clamped on one side in a sliding shoe and swinging up and down in a guide track provided in *a'*. In the example shown in Fig. 5, a number of knives, attached to two endless chains, would be provided. These chains would run at right angles to the rotational axis and guided, in each case, by two rollers mounted in the end walls *a'* and *a³* respectively.

In the embodiment according to Fig. 5, the parts *a'*, *c* and *a³*, as a whole, assume approximately a spherical form. The end wall *a'* is connected to the stationary hollow cylinder *b*, and carries the mixer *m*. *a³* and *c* constitute a unit, are mounted on rollers *r*, and are rotated by means of the toothed crown *z'*. The block is broken down by means of the knife 14 which rocks on the shaft 13 driven by a crank or the like. The reaction mass is moved forward intermittently, and at the moment when the knife 14 is inside the cylinder *b*. The dislodged material is carried away by the conveyor 23. The contact surfaces between *a'* and *c*, and between *a³* and *b*, are self-tightening. *l* is the gas exhaust flue.

The reaction chamber shown in Fig. 6 is in the form of a ring of circular cross section. The stationary cylinder is connected to the end wall *a'*, and the rotary support *c* is connected to the end wall *a³*. The block is broken down by means of a revolving knife disc 14, driven by the pair of pinions *k* and *j*. The toothed crown *z'* serves to drive the support *c*, and the conveyor 23 to remove the dislodged material. *l* is the gas exhaust flue.

What I claim is:—

1. Reaction chamber for the manufacture of superphosphate and like products which comprises one portion which carries the reaction material and which is movable in relation to a second stationary portion the first portion being constructed as a rotational body rotating about a

stationary hollow round shaped body with a horizontal axis.

2. Reaction chamber for the manufacture of superphosphate and like products which comprises one portion which carries the reaction material and which is movable in relation to a second stationary portion the first portion being constructed as a rotational body rotating about a stationary hollow round shaped body with a horizontal axis, this hollow body being provided with a spacious opening for the discharging of the material.

3. Reaction chamber for the manufacture of superphosphate and like products which comprises one portion which carries the reaction material and which is movable in relation to a second stationary portion the first portion being constructed as a rotational body rotating about a stationary hollow round shaped body with a horizontal axis and two end walls one of which being attached to the rotating portion, the other to the stationary portion of the reaction chamber.

4. Reaction chamber for the manufacture of superphosphate and like products which comprises one portion which carries the reaction material and which is movable in relation to a second stationary portion, the first portion being constructed as a rotational body rotating about a stationary hollow round shaped body with a horizontal axis the specific reaction room being separated from the discharging room by an auxiliary wall.

5. Reaction chamber for the manufacture of superphosphate and like products which comprises one portion constructed as a rotational cylinder rotating about a stationary hollow cylinder with a horizontal axis which is provided with a spacious opening for the discharging of the material and carries one of the end walls, the other end wall being attached to the rotating cylinder.

6. Reaction chamber for the manufacture of superphosphate and like products which comprises one portion which carries the reaction material and which is movable in relation to a second stationary portion, the first portion being constructed as a rotational body rotating about a stationary hollow round shaped body with a horizontal axis knives being provided in the reaction chamber to break down the block of superphosphate.

7. Reaction chamber for the manufacture of superphosphate and like products which comprises one portion which carries the reaction material and which is movable in relation to a second stationary portion, the first portion being constructed as a rotational body rotating about a stationary hollow round-shaped body with a horizontal axis revolving knives being provided in the reaction chamber to break down the block of superphosphate.
